AUTOMATIC FIREARM BREECH BOLT LOCK

Hanns Lippert and Ernst Mühlmann, Zurich,
Switzerland, assignors to Verwaltungsgesell-
schaft der Werkzeugmaschinenfabrik Oerlikon,
Zurich-Oerlikon, Switzerland

Application June 27, 1945, Serial No. 601,778
In Switzerland July 8, 1944

1 Claim. (Cl. 89—188)

1

This invention relates to automatic firearms. The invention refers more particularly to gas-operated guns of the type disclosed, for example, in U. S. Patent No. 784,966.

A rigidly locked weapon is known, in which the breech block is locked by a swivelling bolt, the swivelling movement being caused by at least one crank web fitted to the locking bolt; the crank pin of the crank web acts at the same time as a guiding pivot and slides in a corresponding guiding groove of the casing. In this construction the locking bolt slides by means of one-sided tongues in a guiding groove of the breech casing. This guiding groove ends in a round hole in which the locking bolt can swivel in the manner described, coming into contact with the breech casing and thus effecting the locking process.

Weapons are also known, in which the breech block consists of two parts and the locking and release of a locking organ are controlled by the movements of the two breech parts towards, or away from, each other. Such weapons are described, for example, in British Patent No. 575,515.

An object of the present invention is to provide an automatic fire-arm combining the above mentioned characteristics of known weapons, since it has been found that through a suitable combination of these two known characteristics a particularly simple and light breech block could be evolved.

The automatic fire-arm according to the present invention includes a split block body permitting the displacement of the various parts in relation to each other: the front part includes a rotatably mounted locking bolt sliding through its milled ends in a guiding groove of the breech casing terminating in a round hole, and carrying gear teeth in engagement with a gear rack rigidly connected with the lock actuator carrying the hammer, the control taking place through the movements of the block and lock actuator in relation to each other.

The enclosed drawing shows constructional example of the subject of the invention.

Fig. 1 is a schematic section through a weapon with locked breech block.

Fig. 2 shows the weapon according to Fig. 1 with unlocked breech block, in the recoil stroke.

Fig. 3 is a section through the breech block in locked position.

Fig. 4 is a section along line 4—4 in Fig. 3.

Fig. 5 shows the unlocking mechanism.

Fig. 6 is a section through the breech block in unlocked position.

Fig. 7 is a section along line 7—7 in Fig. 6.

2

Fig. 8 shows the mechanism for starting the unlocking process, in its position in the recoil stroke.

Fig. 9 is a perspective view of the locking bolt in locked position.

Fig. 10 is a perspective view of the locking bolt in unlocked position.

The barrel 1 is rigidly fitted in known manner in the breech casing 2. The breech block 3 and the lock actuator 4 slide in the breech casing; a spring 5 is supported in the rear part of the breech casing 2. The breech casing 2 further includes the trigger 6 actuated in known manner. The breech casing 2 is mounted by means of shoulders 7, 8 in a cradle 9, in which it is able to recoil against the spring 10. The cylindrical locking bolt 11 is seated in a hole in the front breech block 3. The locking bolt 11 is provided with a recess 12 into which engages an inserted piece 13 which thus prevents the bolt from moving transversely and from falling out.

The breech block 3 projects into the lock actuator 4 by means of a projection 14. The projection 14 carries shoulders 15 sliding in a hole 16 of the lock actuator 4 and staggered in relation to the shoulders 17, so that the breech block and the lock actuator can be inserted into each other in the manner of a bayonet joint.

As can be seen from Fig. 3, the movement of the breech block and the lock actuator is limited by the shoulders 15 on the breech block 3, and by the shoulders 17 on the lock actuator 4. A gear rack 18 is rigidly connected with the lock actuator; it carries at its front end the firing pin 19 seated in a corresponding hole of the breech block 3. The gear rack 18 engages gear teeth 20 of the bolt 11. The extractor 21 is rotatably mounted in the breech block 3 by means of a pin 22. The extractor 21 stands under the action of a spring 23 inserted in a hole in the breech block 3. That part of the lock actuator 4 which engages below the breech block 3 has a hollow space 24 in which is fitted a T-piece 25 standing under the action of the two springs 26 supported on a front wall of the lock actuator. To the T-piece 25 is fitted a pin 27 projecting through a slot 28 into a hole 29 of the breech block 3 and engaged by a spring 30 fitted in this hole 29. The bolt 11 is provided with two milled ends 31, 32, through which it slides in grooves 33 of the breech casing, ending in a hole 34. The breech block 3 is furthermore provided on its upper face with a stripper 36 rotatably mounted upon a pin 35 and permanently pressed upwards under the action of a spring 37; this

stripper extracts the cartridges out of the belts or magazines.

The unlocking mechanism is shown in Figs. 5 and 8. A hollow cylinder 38 which is open on one side is rotatably mounted upon the barrel or breech casing 2 respectively by means of a pin 39. In the hollow cylinder 38 slides a piston 40 with its rod 41 pivoted to a toggle lever 42 by a pin 43. In the hollow cylinder is arranged a spring 44 projecting into a hole of the piston 40, and tending to force the latter outwards. The toggle lever 42 is swingably mounted on the breech casing by means of the pin 45. The lever 42, through the cam 46, comes into contact with a part 47 rigidly connected with the mounting during the rearward movement of the barrel.

The working of the breech block is briefly as follows:

In the locked position, as shown in Fig. 3, the bolt 11 occupies the position represented in perspective in Fig. 9 and, through its shoulders 31, 32 is in close contact with the breech casing. After the firing the barrel slides rearward. As a result the cam 46 comes into contact with the part 47 rigidly connected with the cradle and revolves round the axis of rotation 45, and therefore under the action of the lever 42, the lock actuator 4 with which it is in contact, is moved rearwards at a speed exceeding by a gradually increasing extent the speed with which the breech block 3 is traveling backwards together with the barrel. As soon as there is relative movement between the breech block 3 and the lock actuator 4, the bolt 11 begins to rotate under the action of the gear rack 18. The bolt 11 with its shoulders 31 and 32 is moved into the position shown in Fig. 10 and is consequently enabled to slide rearwards in the guiding grooves 33. The unlocking is thus effected.

In its rearmost position the breech is again impelled forward by the spring 5. In travelling forward the breech block 3 strikes the cartridge chamber and breech casing and again a relative movement takes place between the breech block 3 and lock actuator 4, since the lock actuator 4 now moves forward in relation to the stationary breech block 3 until the shoulders 15 come into contact with the shoulders 17. Now through the block actuator 4 moving toward the breech block 3, the bolt 11 is caused to revolve under the action of the gear rack 18, and the shoulders 31, 32, come again into contact with the breech casing as shown in Fig. 9, thus effecting the locking. Simultaneously with the forward travel ig-

nition has also taken place, since the gear rack 18 carries the striker as well.

The pin 27 lodged in the breech block 3, in conjunction with the T-piece 25 which, under the action of the springs 26, is in contact with the lock actuator 4, insures that the breech block 3 will always stand under strain in relation to the lock actuator 4, since under the action of the springs 26 the breech block and the lock actuator are permanently drawn toward each other.

As can be seen from the description, the breech block according to the present invention is of extremely simple design; it includes only a few parts and can therefore be made of light weight.

Obviously there would not be the slightest difficulty in using, in lieu of the mechanism shown in Figs. 5 and 8, other driving means or one of the known gas unlocking mechanisms; in other words, the breech block as described can also easily be used in a gas-operated gun.

We claim:

In an automatic fire-arm, locking means comprising in combination a breech block, a locking bolt rotatably mounted in said breech block and having milled ends and gear teeth; a breech casing having guiding grooves formed therein and receiving said milled ends, said breech casing further having a round hole formed therein and in communication with said guiding grooves, a lock actuator movable in relation to said breech block, a gear rack rigidly connected with said lock actuator and meshing with said gear teeth, and a firing pin carried by said gear rack, said milled ends being rotated in said round hole by the gear rack to effect the locking and the release of the locking means.
